UNITED STATES PATENT OFFICE.

HERMAN GOULD, OF UNION HILL, NEW JERSEY.

DESIGN FOR A FLAT LINEN.

Application filed May 6, 1921. Serial No. 467,279. Term of patent 3½ years.

To all whom it may concern:

Be it known that I, HERMAN GOULD, a citizen of the United States, and a resident of Union Hill, in the county of Hudson and State of New Jersey, have invented a new, original, and ornamental Design for Flat Linens, of which the following is a specification, reference being had to the accompanying drawing, which is a plan view showing my new design as applied to flat linens.

I claim:

The ornamental design for a flat linen substantially as shown.

HERMAN GOULD.
